UNITED STATES PATENT OFFICE.

JOSEPH N. MAHONEY, OF WILKINSBURG, AND WALTER M. AUSTIN, OF SWISSVALE, PENNSYLVANIA, ASSIGNORS TO WESTINGHOUSE ELECTRIC AND MANUFACTURING COMPANY, A CORPORATION OF PENNSYLVANIA.

ELECTRICAL PROTECTIVE DEVICE.

1,264,415.

Specification of Letters Patent.

Patented Apr. 30, 1918.

Application filed April 3, 1914. Serial No. 829,300.

To all whom it may concern:

Be it known that we, JOSEPH N. MAHONEY, a citizen of the United States, and a resident of Wilkinsburg, in the county of Allegheny and State of Pennsylvania, and WALTER M. AUSTIN, a citizen of the United States, and a resident of Swissvale, in the county of Allegheny and State of Pennsylvania, have invented a new and useful Improvement in Electrical Protective Devices, of which the following is a specification.

Our invention relates to electrical protective devices, and particularly to reverse-current and underload tripping devices for circuit interrupters.

The object of our invention is to provide a reverse-current and underload tripping device of such construction that its magnetic flux will not traverse the pivotal parts and thus impede their operation.

Devices have heretofore been provided for tripping circuit interrupters when the direction of the current becomes reversed, as it frequently does in interconnected distributing systems, but such devices have been expensive to construct and the pivotal parts of the same have been magnetized to such an extent as to impair their accuracy of operation.

In our invention, we provide a simple and inexpensive reverse-current tripping device which obviates the hereinbefore mentioned difficulty and which may be adjusted to operate when the current traversing a circuit falls to any predetermined value.

Figure 1 of the accompanying drawing is a side elevational view of a circuit interrupter embodying our invention, Fig. 2 is a front elevational view of the device shown in Fig. 1, and Fig. 3 is a detail view, partially in section and partially in elevation, of a device embodying our invention.

A circuit interrupter 1 is mounted upon a panel 2 and comprises two main stationary contact members 3 and 4, a secondary stationary contact member 5, a tertiary stationary contact member 6 and brackets 7 and 8 upon which are pivotally mounted an arm 9 carrying a movable contact member 10 for engaging the contact member 6 and a second movable arm 11 comprising a

resiliently mounted member 12 for engaging the stationary contact member 5, a laminated bridging member 13 that is pivotally mounted thereon, and a cam member 14, substantially as shown. The lever arm 11 extends through an opening in the lever arm 9 and they are connected together by springs 15, for purposes hereinafter described. An operating lever arm 16 has a roller member 17 at one end thereof for engaging the cam member 14, and it also has two projections 18 and 19 that extend substantially at right angles therefrom. Spiral springs 20 connect the projection 18 to the arm 11, substantially as shown. The projection 19 of the operating lever arm 16 engages a latch 21 which is tripped either by an overload tripping coil 22, a manually operated handle 23 or by a reverse-current and underload tripping device 24 which embodies our invention.

The tripping device 24 comprises a coil 25 that is disposed around a magnetizable core member 26 and is connected to the stud of the contact member 4 and to an auxiliary terminal 27. The magnetizable core member 26 is of substantially U-shape and has depending from each leg thereof two auxiliary core members 28 and 29 and 30 and 31, respectively, upon which are respectively disposed series-connected windings 32, 33, 34 and 35 the circuit comprising which is connected in shunt relation to the circuit that is to be protected. The windings 32, 33, 34 and 35 are so connected that they form alternate magnetic poles of which the core members 29 and 31 have the same polarity, and the core members 28 and 30 have a polarity which is opposite to that of the members 29 and 31. Two brackets 36 are provided, and, pivotally mounted upon these brackets is a movable member 37 upon the inner end of which is mounted a magnetizable member 38. The member 37 is also provided with a counter-balance weight 39, a guiding member 40 for the counter-balance weight 39, and an actuating thumb screw 41 for setting the counter-balance weight 39 in any desired position. To the member 37 is attached an adjustable screw 42 for engaging a rod 43 which is normally held in its lower position by a spiral spring

44. The rod 43 engages a bell crank lever 45 to operate the latch 21 through a connecting rod 46.

The magnetizable core member 26 is energized in such manner that it increases the magnetization of the auxiliary core members 28 and 31, respectively. The magnetizable member 38 is attracted by each of the auxiliary electromagnets, as will be well understood by those versed in the art. However, the tendency for the same to move downwardly is the greatest by reason of the magnetization of the magnetizable core member 26, as hereinbefore mentioned. When the current flowing through the coil 25 reverses in direction, by reason of the common faults so often perceptible in interconnected distributing systems, the magnetizable member 26 will be attracted more strongly in the opposite direction from that in which it is normally attracted and thus the movable member 38 will be quickly overbalanced and moved upwardly to operate the latch 21 through the rod 43, bell crank lever 45 and rod 46 to trip the circuit interrupter 1.

The operating lever 16 of the circuit interrupter 1 moves upwardly when the projection 19 is released by the latch 21 to allow the roller 17 to move over the face of the cam member 14 and thus cause the springs 20 to operate the bridging contact member 13 and the secondary contact member 12, successively. The disengaging of these contact members forces the disengagement of the contact members 6 and 10, as will be readily understood.

The reversed current at which the circuit interrupter 1 is tripped may be adjusted by operating the thumb screw 41 to change the position of the counter-balance weight 39 with respect to the pivotal point of the member 37, as will be understood.

Since the magnetizable member 38 is disposed between the poles of the several auxiliary electromagnets, the magnetic lines of force will not traverse the bracket 36 to impede the operation of the movable member 37 by magnetizing the pin 47 upon which it is mounted. A stop 48 is located on one of the brackets 36 for preventing too great a movement of the member 38 in a downwardly direction, as will be readily seen.

The windings may be omitted from one of the alternately disposed core members on each leg of the core member 26, thus providing two consequent poles. The operation of the device with the two windings will be substantially the same as was described with respect to the device with the four windings.

By adjusting the position of the weight 39 and the position of the screws 42, the device may be caused to operate when the current traversing the coil 25 falls below a predetermined value, as will be understood.

While we have described our invention in connection with a circuit interrupter of definite construction it is not so limited but is capable of various adaptations within the scope of the appended claims.

70

We claim as our invention:

1. An electrical protective device comprising a magnetizable core member, four electromagnets depending therefrom to constitute alternate magnetic poles, a movable core member pivotally mounted between the core members of said electromagnets, and means for so balancing the said pivotally mounted core member that, when the magnetic lines of force change in the said magnetizable core member, the pivotally mounted core member is attracted in a predetermined direction.

2. In a circuit protective device, the combination with a circuit interrupter, of a tripping device therefor comprising a magnetizable core member in operative relation to one terminal of the said circuit interrupter, a plurality of projections on said magnetizable core member, windings for the said projections for forming alternate magnetic poles, a pivotally mounted movable member disposed between the projections of said magnetizable core member, and means whereby the pivotally mounted movable member trips the circuit interrupter when the current reverses.

3. In a circuit protective device, the combination with a circuit interrupter, of a reverse-current tripping device therefor comprising a magnetizable core member, means for magnetizing the core member in accordance with the current traversing the circuit, auxiliary core members depending from the core member, windings for the auxiliary core members for forming alternate magnetic poles, a movable member pivotally mounted at a point intermediate its ends, a magnetizable member located at one end thereof, and means whereby the said movable member will trip the said interrupter when the current reverses.

4. In a circuit protective device, the combination with a circuit interrupter, of a reverse-current tripping device therefor comprising a magnetizable core member adapted to be magnetized in accordance with the current traversing the circuit, auxiliary core members depending therefrom, windings disposed on the said auxiliary core members to constitute alternate magnetic poles, a movable member pivotally mounted at a point intermediate its ends, a magnetizable member located at one end thereof, a counter-balance weight operatively connected thereto, and means whereby said movable member will trip the said interrupter when the current reverses.

5. In a circuit protective device, the combination with a circuit interrupter, of a re-

- verse-current tripping device therefor comprising a magnetizable core member adapted to be magnetized in accordance with the current traversing the circuit, auxiliary core members depending therefrom, windings for the said auxiliary core members adapted to produce alternate magnetic poles, a movable member pivotally mounted at a point intermediate its ends, a magnetizable member located at one end thereof, a counter-balance weight operatively connected thereto, means for adjusting the relative position of said counter-balance weight, and means whereby said movable member will trip said interrupter when the current therein reverses.
6. In a circuit protective device, the combination with a circuit interrupter, of a reverse current tripping device therefor comprising a magnetizable core member, means for magnetizing the same in proportion to the current traversing the said interrupter, two auxiliary core members depending from each pole of said magnetizable core member, means for magnetizing said auxiliary core members to constitute alternate magnetic poles, brackets, a movable member pivotally mounted on said brackets at a point intermediate its ends, and a magnetizable member on the inner end of said movable member and disposed between the two auxiliary core members on each pole of said magnetizable core member.
7. A tripping mechanism for a circuit interrupter comprising a magnetizable core member adapted to be energized in accordance with the current traversing the interrupter, a plurality of laterally-extending core members operatively connected thereto, means for energizing the laterally-extend-

ing core members to constitute alternate magnetic poles, and a pivotally-mounted movable core member disposed between the laterally-extending core members and adapted to be actuated when the current traversing the circuit interrupter reverses in direction.

8. The combination with a circuit interrupter, of a magnetizable core member energized in accordance with the current traversing the circuit interrupter, a plurality of projections on the magnetizable core member, means for energizing the projections to constitute alternate magnetic poles, and a pivotally-mounted movable core member disposed between the said projections and adapted to be actuated under predetermined conditions.

9. The combination with a circuit interrupter, of a reverse-current tripping device therefor comprising a magnetizable core member adapted to be energized in accordance with the current traversing the interrupter, auxiliary core members projecting thereon, means for energizing the said auxiliary core members to constitute alternate magnetic poles, and a movable magnetizable member pivotally mounted at a point intermediate its ends and adapted to be actuated when the current reverses in the circuit in- 70

In testimony whereof, we have hereunto subscribed our names this 31st day of March, 1914.

JOSEPH N. MAHONEY.
